UNITED STATES PATENT OFFICE.

EDWARD KRONMAN, OF NEW YORK, N. Y.

DESIGN FOR A STERILIZING-RECEPTACLE.

No. 38,898.

Specification for Design.

Patented Nov. 26, 1907.

Application filed July 18, 1907. Serial No. 384,489. Term of patent 14 years.

To all whom it may concern:

Be it known that I, EDWARD KRONMAN, a citizen of the United States, residing in the borough of Manhattan, New York city, county and State of New York, have invented a new and original Design for Sterilizing-Receptacles, of which the following is a specification, reference being had to the accompanying drawings, forming a part thereof.

In the drawings, Figure 1 is a side view and Fig. 2 is an end view of a receptacle or body of a sterilizer, showing my new design.

I claim;—

The ornamental design for a sterilizing receptacle, as shown.

EDWARD KRONMAN.
